UNITED STATES PATENT OFFICE.

CLARA V. HAVENS, OF NEW YORK, N. Y., ASSIGNOR TO THE KARMEN CORPORATION, OF NEW YORK, N. Y., A CORPORATION OF NEW YORK.

DESIGN FOR A DOLL.

Application filed November 1, 1923. Serial No. 7,646. Term of patent 14 years.

To all whom it may concern:

Be it known that I, CLARA V. HAVENS, a citizen of the United States, residing in the city of New York, borough of Manhattan, in the county and State of New York have invented a new, original, and ornamental Design for Dolls, of which the following is a specification, reference being had to the accompanying drawings, forming part thereof.

I claim:

The ornamental design for a doll as shown.

CLARA V. HAVENS.
